US00D748136S

(12) **United States Design Patent**
Lee et al.

(10) **Patent No.:** US D748,136 S
(45) **Date of Patent:** ** Jan. 26, 2016

(54) **DISPLAY SCREEN OR PORTION THEREOF
WITH ICON**

(71) Applicant: **Samsung Electronics Co., Ltd.**,
Suwon-si (KR)

(72) Inventors: **Bo-Young Lee**, Seoul (KR);
Seung-Kyung Lim, Seoul (KR); **Ji-Hye
Myung**, Yongin-si (KR)

(73) Assignee: **Samsung Electronics Co., Ltd.**,
Suwon-si (KR)

(**) Term: **14 Years**

(21) Appl. No.: **29/458,119**

(22) Filed: **Jun. 17, 2013**

(30) **Foreign Application Priority Data**

Feb. 23, 2013 (KR) 30-2013-0009532

CLAIM

The ornamental design for a display screen or portion thereof with icon, as shown and described.

DESCRIPTION

FIG. 1 is a front view of a display screen or portion thereof with icon, showing our new design;

FIG. 2 is a front view of a second embodiment thereof; and, FIG. 3 is a front view of a third embodiment thereof. The broken lines represent a boundary and form no part of the claimed design.

1 Claim, 3 Drawing Sheets
